(57) **CLAIM**

The ornamental design for a bottle neck identification ring, as shown and described.

DESCRIPTION

FIG. 1 is a perspective view of a bottle neck identification ring depicting the new design;

FIG. 2 is a front elevational view of the bottle neck identification ring depicted in FIG. 1;

FIG. 3 is a rear elevational view of the bottle neck identification ring depicted in FIG. 1;

FIG. 4 is a bottom elevational view of the bottle neck identification ring depicted in FIG. 1;

FIG. 5 is a top elevational view of the bottle neck identification ring depicted in FIG. 1;

FIG. 6 is a right side elevational view of the bottle neck identification ring depicted in FIG. 1;

FIG. 7 is a left side elevational view of the bottle neck identification ring depicted in FIG. 1;

FIG. 8 is a perspective view of the bottle neck identification ring depicted in FIG. 1, shown as it appears in a typical use.

FIG. 9 is a front elevational view of the bottle neck identification ring depicted in FIG. 1, shown as it appears in a typical use.

FIG. 10 is a rear elevational view of the bottle neck identification ring depicted in FIG. 1, shown as it appears in a typical use.

FIG. 11 is a bottom elevational view of the bottle neck identification ring depicted in FIG. 1, shown as it appears in a typical use.

FIG. 12 is a top elevational view of the bottle neck identification ring depicted in FIG. 1, shown as it appears in a typical use.

FIG. 13 is a right side elevational view of the bottle neck identification ring depicted in FIG. 1, shown as it appears in a typical use; and,

FIG. 14 is a left side elevational view of the bottle neck identification ring depicted in FIG. 1, shown as it appears in a typical use.

The broken lines showing in the drawings depict environmental subject matter only and form no part of the claimed design.
